UNITED STATES PATENT OFFICE.

WILLIAM TREVENA WILLIAMS IDRIS AND WILLIAM OLIVER ROSS, OF LONDON, ENGLAND, ASSIGNORS TO IDRIS & CO., LIMITED, OF LONDON, ENGLAND.

SIPHON FOR AERATED LIQUIDS.

1,109,291.

Specification of Letters Patent.

Patented Sept. 1, 1914.

Application filed December 5, 1913. Serial No. 804,933.

To all whom it may concern:

Be it known that we, WILLIAM TREVENA WILLIAMS IDRIS and WILLIAM OLIVER Ross, subjects of the King of Great Britain, residing, respectively at 244 Camden road, Camden Town, London, England, and 32 Westfield road, Hornsey, London, England, have invented new and useful Improvements in Siphons for Aerated Liquids, of which 10 the following is a specification.

This invention relates to siphons in which the nozzle and valve seat are formed in a single block generally of porcelain and the like.

15 According to this invention the lower part of the siphon head which screws onto the usual split ring is forked or slotted and the block is so formed that it projects between the forks or through the slots in two or more 20 places. The block is kept in position by a ring fitting around the outside of the head, the lower edge of which bears upon a flange on the split ring while its upper edge bears against the projecting portions of the block. 25 The ring may be prevented from turning by internal segmental lugs which fit between the forks or in the slots in the head.

The invention is applicable both to long and short lever siphons.

30 Figures 1 and 2 are vertical sections at right angles to each other of a siphon top constructed according to this invention. Figs. 3 and 4 are sections on the lines A—A and B—B Figs. 1 and 2. Fig. 5 is a detached 35 elevation of the lower part of the siphon head.

1 is the vase, 2 the block and 3 the washer between them.

4 is the central tube and 5 is the split ring.

40 6 (Fig. 5) is the lower part of the siphon top provided with an internal screw thread 7 for screwing onto the split ring and an

external screw thread 8 onto which screws the cap 9. The part 6 as shown has in it two vertical slots through which the block 2 projects. The projecting portions of the block being dovetailed as shown at Fig. 4 so that the block is firmly held and cannot be moved sidewise relatively to the part 6. The block is prevented from moving downward (when 50 the head is in place) by the ring 10 which fits outside the part 6.

55 11 are segmental lugs in the ring 10 which fit the slots in the part 6. The slots may be at the top of the part 6 instead of at the bottom.

What we claim is:—

1. In a siphon head the combination of a split ring, a casing screwing onto the split ring and having in it at its lower end a plurality of slots, a block the body of which is adapted to fit the casing and having upon it a plurality of projections adapted to fit the slots, and a ring fitting around the lower part of the casing and having its ends abutting against the block and the split ring respectively. 60

2. In a siphon head the combination of a split ring, a casing screwing onto the split ring and having in it at its lower end a plurality of slots, a block the body of which is adapted to fit the casing and having upon it a plurality of projections adapted to fit the slots, a ring fitting around the lower part of the casing and having its ends abutting against the block and the split ring respectively and lugs fixed inside the ring and adapted to fit the lower part of the slots. 70 75

WILLIAM TREVENA WILLIAMS IDRIS.
WILLIAM OLIVER ROSS.
